TEA POT, &c.

No. 19,192.

Patented July 2, 1889.

UNITED STATES PATENT OFFICE.

WILLIAM HENRY SILLS, OF CHICAGO, ILLINOIS.

DESIGN FOR A TEA-POT, &c.

SPECIFICATION forming part of Design No. 19,192, dated July 2, 1889.

Application filed May 1, 1889. Serial No. 309,293. Term of patent 7 years.

To all whom it may concern:

Be it known that I, WILLIAM HENRY SILLS, a citizen of the United States, residing in Chicago, in the county of Cook and State of Illinois, have invented and produced a new and original Design for Tea-Pots, &c., of which the following is a specification.

This invention relates to a design for metal tea-pots and similar vessels, and is fully shown in the accompanying cut, forming a part of this specification, and in which—.

A represents the body of the pot; B, the cover, C the handle, D the spout, and E the bottom, thereof.

The body is figured near the top with the belt of ornamentation m, the same consisting of heart-shaped figures with the points uppermost, a leaf filling in each of said figures, and a row of beading above and below the figures.

Surrounding the opening at the top and above the ornamentation m is a row of short vertical corrugations n. Running around the lower edge of the body is another belt of embossed ornamentation o, similar to the belt m, except that the heart figures are placed with their points downward. Between the belts m and o the body is impressed with a checkered design p, consisting of squares arranged diagonally. Each square may be filled with lines in a direction at right angles to its neighbor squares, as indicated.

The cover B is figured to represent a series of overlapping spatula-like figures b, the same being arranged in lines radiating from the knob or handle h at the center of the cover.

I claim—

1. The design for a tea-pot or other similar vessel herein set forth.
2. The design for the body of a tea-pot or other similar vessel herein set forth.
3. The design for the cover of a tea-pot or other similar vessel, as herein set forth.

WILLIAM HENRY SILLS.
